UNITED STATES PATENT OFFICE.

WARREN E. ENDICOTT, OF PAWNEE, OKLAHOMA.

RESILIENT WHEEL.

1,158,795.

Specification of Letters Patent.

Patented Nov. 2, 1915.

Application filed September 14, 1914. Serial No. 861,698.

To all whom it may concern:

Be it known that I, WARREN E. ENDICOTT, a citizen of the United States, residing at Pawnee, in the county of Pawnee and State of Oklahoma, have invented certain new and useful Improvements in Resilient Wheels, of which the following is a specification, reference being had to the accompanying drawings.

10 This invention relates to new and useful improvements in resilient wheels and particularly to that class of wheels which are provided with spring spokes.

15 An object of this invention is to simplify the construction of devices of this character whereby to render the same more commercially desirable and efficient and durable in use.

20 A further object of this invention is the provision of a spring spoke for vehicle wheels which is provided with telescoping sections, comprising a pair of spaced cylinders having a plunger disposed therebetween, springs being so arranged in the 25 plungers that a portion of the spokes of the wheel will be allowed to contract while another portion thereof expands.

With these and other objects in view, my 30 invention consists in the novel construction, combination, and arrangement of parts, to be hereinafter more fully described, claimed, and illustrated in the accompanying drawing, in which—

Figure 1 is a fragmentary side elevational 35 view of my improved wheel; and Fig. 2 is a sectional view on the line 2—2 of Fig. 1.

Referring more particularly to the drawing, the numeral 1 designates the hub of my improved wheel in which a plurality of recesses 2 are formed, and 3 the rim of the wheel from which a plurality of spaced bifurcated stems 4 project inwardly, the stems being of the same number as the recesses, and being spaced apart suitable distances 45 so as to be in radial alinement with the recesses. Each of my improved spokes comprises three sections, the sections including an inner and an outer cylinder 5 and 6 respectively, the cylinders being closed at 50 their opposing ends, a plunger 7 being disposed between the cylinders and projecting at its opposite ends within the same through the closed ends thereof. To close the inner end of the inner cylinder 5 and the outer 55 end of the outer cylinder 6, caps 8 are threadably mounted thereon, each of the

caps having a longitudinally projecting apertured lug 9, the lug 9 on the inner cylinder being pivotally mounted in one of the recesses 2 in the hub, and the lug on the outer cylinder being pivotally mounted between the furcations of the stem 4 which is in radial alinement with the recess. Disposed within each of the cylinders is a coiled spring 10, and threadably mounted on each end of the plunger 7 is a head 11, the heads being adapted for engagement against the springs contained within the cylinders. The head 11 on the inner end of the plunger is arranged between the outer end of the cylinder 5 and the outer end of the spring 10 contained therein, and the head on the outer end of the plunger 7 is arranged between the cap 8 in the outer end of the cylinder 6 and the spring 10 contained therein whereby 75 each of the plungers is held in the outer end of its cylinder. It will be noted from Fig. 1 that the space between the cylinders 5 and 6, when these cylinders are arranged in operative position and engaged with the heads 80 or caps 8, is equal to the length of either one of the cylinders but greater than the length of the springs. Thus either cylinder may be detached from its corresponding cap and shifted along the plunger rod to 85 permit the removal of the corresponding spring from the cylinder. Thus if either of the springs in my construction is damaged it is only necessary to unscrew the corresponding cylinder from the corresponding cap and shift the cylinder longitudinally along the plunger rod whereby the corresponding spring may be readily removed. Furthermore, it is an easy matter to remove 90 the plunger in case this is necessary. Thus 95 both of the cylinders may be unscrewed from their respective caps and one of the cylinders is shifted back upon the plunger rod, the corresponding head of the plunger rod removed, and then the plunger rod may 100 be removed from between the cylinders. If one of the cylinders is damaged in any way it is relatively an easy matter to replace it in a few minutes.

In the foregoing description, I have only 105 specifically described one spoke, but it will be readily understood from the drawing that any desired number of spokes may be used in connection with the hub and rim, so that all of the spokes are identical in 110 construction.

In assembling my improved wheel, the

rim 3 is arranged concentric to the head, and the opposite ends of the plungers 7 are disposed through the opposing end walls of the inner and outer cylinders. The springs 5 are then placed within the outer cylinders 6, whereupon the heads 11 are threaded on the outer ends of the plungers to bear against the outer ends of the springs, and the caps 8 are then threaded on the outer ends of the cylinders 6. The cylinders 5 are moved inwardly on the plungers so that the heads 11 may be threaded upon the inner ends of the plungers, whereupon the cylinders are again moved outwardly on the plungers to engage the heads 11 on the inner ends of the plungers against the outer end walls of the cylinders, so that the springs may be placed into the inner cylinders and the caps 8 threaded upon their inner ends. With the various parts in this position, the lugs 9 on the outer ends of the cylinders 6 are pivotally mounted between the furcations of the stems 4 and the lugs 9 on the inner ends of the cylinders 5 are pivotally mounted with 25 in the recesses 2 and the wheel is then ready for use. As the wheel is used, it will be readily understood that the spokes below the hub will be compressed, and the spokes above will be lengthened, the arrangement 30 of the springs within the cylinders allowing for automatic lengthening and shortening of the spokes as the wheel rotates. It will of course be understood that if desired

a rubber tire may be mounted on the rim 3 to deaden the noise of the wheel as the same 35 moves over a rough roadway.

Having thus fully described my invention, what I desire to claim and secure by Letters Patent is:—

In a resilient wheel, a hub, a rim, a plurality of spokes connecting the hub and rim, each spoke comprising a rod having a head at each end, a pair of cylinders into which the opposite ends of the plunger rod are disposed for sliding movement, the confronting ends of the cylinder being permanently closed, caps closing the oppositely directed open ends of the cylinders, the caps being respectively pivotally connected to the rim and to the hub, a spring disposed in one cylinder between the permanently closed end thereof and the plunger head, and a spring disposed in the other cylinder between the cap thereof and the plunger head, the space between the cylinders being sufficient to permit either cylinder to be shifted along the plunger rod to entirely disclose the corresponding spring and permit its removal.

In testimony whereof I hereunto affix my 60 signature in the presence of two witnesses.

WARREN E. ENDICOTT.
